REPLACEABLE WHEEL AND TRACK PAD
Louis Speidel, Jr., Royal Oak, and Edward J. Gow, Jr.,
Oak Park, Mich., assignors to the United States of
America as represented by the Secretary of the Army

Filed Apr. 25, 1961, Ser. No. 105,523

4 Claims. (Cl. 305—38)

(Granted under Title 35, U.S. Code (1952), sec. 266)

The invention described herein may be manufactured and used by or for the Government for governmental purposes, without the payment to us of any royalty thereon.

This invention relates to a track shoe with a replaceable wheel and track pad.

More particularly, this invention relates to an endless track composed of track shoes provided with a molded rubber pad which can be installed in the cavity of the track shoe to form both the wheel pad and road pad. The pad requires no bond to the track shoe, but is mechanically fixed in place.

This invention is in the nature of an improvement over prior art devices, such as that disclosed by the patent to Christmas, Patent No. 2,162,700. The Christmas patent provides a track shoe with a molded rubber pad mechanically installed in a cavity of the track shoe to form both the wheel pad and road pad. The track pad is also utilized as a mounting for a pair of link pins which connect adjacent shoes and serve to reinforce the track pad. The pins, track shoe, and pad are assembled by forcing the pad into the cavity of the track shoe and then passing the pins through aligned passages in the track shoe and associated pad. The endless track is completed by connecting the projecting ends of each link pin to the projecting ends of the link pin in the nearest adjacent track shoe.

The Christmas device is considered inadequate for a number of reasons. When the endless track of Christmas device begins moving around the drive sprocket there is a tendency for the link pins to turn within the track pad. This causes friction and undue wear on the track pad resulting in early failure. Further, when it is desired to replace a worn pad, it is necessary first to disconnect the track shoe containing the worn pad from the two adjacent shoes (thus opening the endless track), and then pull the two link pins out of engagement with the track shoe and pad. This finally places the worn pad in position to be removed and replaced.

The object of our invention is to provide a track shoe and pad wherein a worn pad can be replaced without opening the endless track or disengaging the link pins.

A further object of our invention is to provide a track shoe and pad wherein the pad is not subjected to wear caused by the rotation of link pins.

A further object of our invention is to provide a track shoe and pad wherein the pad is furnished with internal reinforcing.

Other objects and advantages will appear to those skilled in the art from the following description and appended claims as well as from the accompanying drawings, in which—

FIG. 1 is a partial plan view of the wheel side of the prior art endless track.

FIG. 2 is a plan view of the road side of the track shoe and pad of our invention.

FIG. 3 is a plan view of the wheel side of the track shoe and pad of our invention.

FIG. 4 is a partial sectional view through line 4—4 of FIG. 3 with parts being broken away.

The prior art device discussed above is illustrated in FIG. 1.

The endless track of our invention consists of a series

2

of track shoes 2 connected and held together by link pins (not shown) passing through aligned bearings 4 and 6.

The track shoes 2 are all identical and each comprises a metal band 8 to which grouser portions 10 and bearing 4 are integrally attached. Bearing 6 is, in turn, integrally attached to grousers 10. The inner walls of metal band 8, as best seen in FIG. 4 of the drawings, are tapered toward a horizontal plane through the center of band for a purpose made clear hereinafter.

10 Although the specific details of the track shoe construction are described and shown, they are not considered part of the invention, and it is to be understood that this invention is not limited to use with a specific track shoe but is to be considered equally useful with track shoes of 15 different designs.

A block 12 of rubber or rubber-like material, having side walls complementary to the band 8, but having a volume slightly greater than that enclosed by band 8, is compressed into band 8. The block is reinforced by an 20 exaggerated T-shaped metal bar 14, bonded to the block at the time the block was formed and vulcanized. The compression fit of the rubber block 12, the tapered walls of band 8 plus the bolts 16, 18, 20, connecting bar 14 to the track shoe 2, all maintain the rubber block 12 in 25 tight engagement with band 8, and make the use of adhesives unnecessary.

The block 12 thus installed within band 8 forms both the wheel pad 22 and the road pad 24 of track shoe 2. The portion 26 shown in FIG. 4 extending past the en- 30 circling band 8 is provided to protect the band from abrasive contact with the roadway. Guide members 28 and 30 are located centrally of the shoe, occurring as raised portions of the web 32 which is integral with the body of the track shoe 2.

35 The fact that block 12 is not utilized as a bearing for the link pins of the endless track, prolongs the life of the block and enables removal of a worn block without the necessity of opening the endless track.

It is understood that various modifications may be 40 apparent to those skilled in the art without departing from the spirit and scope of the invention, and the invention is not to be limited to the illustrated embodiments except as included in the appended claims.

We claim:

45 1. An endless track, embodying articulated track shoes, each shoe comprising a metal band, a pair of spaced bearings on each longitudinal side of said shoe, corresponding bearings of adjoining track shoes being in alignment when link pins are inserted through aligned bearings 50 of adjoining shoes, a block of rubber or rubber-like material compressed into said band and having its outer and inner parallel surfaces exposed to serve as both a wheel pad and a road pad for said shoe and a reinforcing bar bonded within said block, the ends of said bar being 55 detachably secured to the inner walls of said band.

2. The endless track of claim 1 wherein the inner walls of said band are tapered from each edge toward a horizontal plane drawn through the center of said band, said block having edges formed with V-grooved channels complementary to the tapered inner walls of said band.

60 3. The endless track of claim 2 wherein the reinforcing bar is T-shaped.

4. In an endless track embodying articulated track shoes, each shoe comprising a metal band enclosing a substantially rectangular area, said band having its inner walls tapered inwardly from each edge toward a horizontal plane drawn through the center of said band, a pair of spaced bearings on each longitudinal side of said band, corresponding bearings of adjoining track shoes being in alignment when link pins are inserted through aligned bearings of adjoining shoes, a block of rubber

or rubber-like material compressed into said band and having its outer and inner parallel surfaces exposed to serve as both a wheel pad and a road pad for said shoe, said block having edges formed with V-grooved channels complementary to the tapered inner walls of said band, 5 said block having a height greater than said band, and a T-shaped reinforcing bar bonding within said block, the three ends of said T-bar being detachably secured to said

band, said T-bar lying in a plane perpendicular to said block surfaces.
